UNITED STATES PATENT OFFICE.

WILBER J. PINE, OF OSHKOSH, WISCONSIN.

WIRE FABRIC.

1,376,037.

Specification of Letters Patent. Patented Apr. 26, 1921.

Application filed July 23, 1917. Serial No. 182,268.

To all whom it may concern:

Be it known that I, WILBER J. PINE, a citizen of the United States, residing at Oshkosh, county of Winnebago, and State of Wisconsin, have invented new and useful Improvements in Wire Fabrics, of which the following is a specification.

My present invention relates to new and useful improvements in wire fabrics of a resilient nature, and particularly adapted for use in connection with spring mattresses.

It is in general my object to increase the strength of fabrics of this nature particularly as against severe load conditions, without under normal conditions lessening the desired maximum resilient distribution of load stress throughout the fabric with respect to the individual units and without adding materially if at all to the cost and difficulty of manufacturing.

It is more particularly my object to provide a fabric composed of units forming longitudinal lines of support which are capable of resilient transverse yielding under normal conditions broadly in the manner set out in my copending application filed June 11, 1917, Serial No. 173,953, but wherein direct longitudinal connections are afforded upon the occurrence of relatively great load stress, to provide sufficient strength against such stress.

A more detailed object is to provide a fabric including units having transverse connecting arms projecting therefrom in such manner as to resiliently resist relative longitudinal movement of transversely adjacent units.

With the above and other objects and advantages in view, the invention resides more particularly in the novel combination, formation and arrangement of parts herein-after described and pointed out in the appended claims.

In the drawings:

Fig. 1 is a plan view of a pair of connected units forming a portion of my improved fabric.

Fig. 2 is a transverse sectional view on the line 2—2 of Fig. 1.

Fig. 3 is a view similar to Fig. 1, but showing a modified form of fabric unit.

Fig. 4 is a transverse sectional view on the line 4—4 of Fig. 3.

Referring now more particularly to the accompanying drawings, my improved fabric is formed of a series of units mutually

connected longitudinally and transversely of the fabric, and in Fig. 1 each of these units is formed of a single length of wire bent upon itself at a substantially central point 5 to form a pair of slightly convergent shanks 6, the end portions of the length of wire being bent outward in opposite directions to form connecting arms 7, these arms being considerably shorter than the shanks 6 and being bowed outwardly at their inner ends at 8 whereby to curvingly merge into the ends of the shanks 6. By forming the curved connecting loop 5 in the manner illustrated by Figs. 1 and 2, this curved loop is in a plane spaced from the plane of the shanks 6 and is substantially in the plane of the outwardly extending short arms of the adjacent unit of the fabric, while the curved hooks 9 which join the loop 5 with the shanks 6 are formed in other and parallel planes so their mouths are closed by the loop 5. For connecting the ends of the shanks of longitudinally adjacent series and for permitting a transverse resilient relative movement of the shanks when so connected, the end of each of the shanks adjacent the bend 5 is partially folded or doubled upon itself to thereby dispose said bend intermediate of the completed lengths of the shanks thus forming downwardly turned hook members 9 at the ends of the shanks adapted to engage the portions 8 of the next succeeding unit. These hook members 9 have their extremities connected by the portion 5 and as shown more particularly in Fig. 2 the units may if desired be loosely held in interlocking relation against any possible disengagement by bending the portion 5 to close the mouths of the hooks 9. The free end of the connecting arm 7 is bent to form an eye-loop 10 located in a horizontal plane, the extremity of this arm being bent about the intermediate portion of the arm at 10' to securely hold the eye closed under load stress. The outer end of the other arm 7 is bent to form an eye-loop 11 located in a vertical plane and adapted for engagement in the eye-loop 10 of a transversely adjacent unit.

Thus the entire completed fabric may be formed of series of identical units, each formed in a simple manner from a single length of wire, to facilitate ease and the cheapness of manufacture.

In assembling the longitudinal series of units, the connecting arms 7 and adjacent

105

110

- shank portions of one unit are inserted between the shanks of a succeeding unit to procure an interlocking engagement of the shank hooks 9 of the second unit with the shank and arm junctures of the first unit, the hook mouths being then closed as set forth. The units are transversely connected by interlocking the eyes 10 and 11 in any convenient manner.
- 10 The series of longitudinal shanks 6, directly connected at their ends, thus afford longitudinal straight lines of support in the completed fabric which will efficiently support an excessive load stress. At the same time, by the disposition of the connecting portions of the shanks intermediate of their ends, to permit a resilient lateral relative movement, a supporting action similar to that set up in my aforesaid co-pending application is procured, providing for a resilient transverse resistance within the occupied portion of the mattress to take up the sagging tendency of the fabric between the points of pressure afforded by the salient portions of a person's body.
- 15
- 20
- 25

This action is procured by the transverse pull exerted by the connecting arms 7 on the shanks at the points of greatest pressure to thus provide for the additional width and yielding of the fabric body at said points, the remaining portions of the fabric being under lesser transverse strain to permit a more normal relation of the shanks 6. The curved junctures of the shanks and arms 30 permit an easy relative movement of the attaching hooks to effect this action. The bowed portions 8 also provide for a considerable transverse stretching action of the connecting arms 7 under load conditions.

- 35
- 40
- 45
- 50

The arms 7 transversely connecting the units extend integrally outward from their respective shanks and will thus resiliently oppose relative longitudinal movement of the units is dependent in no manner upon the relative transverse movements of the shanks to take up the sag at intermediate points of the mattress when occupied.

55

60

65

It will be observed that the arcuate portion 8 between shank 6 and arm 7 has a gradual curve so that under a longitudinal strain the seat of the shank hooks 9 will be offset from the axis of the shank 6. Hence any such longitudinal strain tends to flex the elbow 8 and displace angularly the arm

7. Such a longitudinal strain is resiliently opposed by the natural tendency of the metal to retain its shape and by the connection of arm 7 with adjacent units, whereby its resistance to displacement is proportioned to the amount of strain tending to distend the

fabric laterally. Thus the fabric will yield resiliently to a longitudinal strain as well as to a transverse strain as heretofore explained.

My improved fabric unit comprises essentially a pair of L-shaped sections, the shanks of which are suitably connected together, and as shown in the modified units of Figs. 3 and 4 this structure need not necessarily be integral to retain the major advantages set out in the specific structure heretofore described. In this modified form there are provided a pair of L-shaped sections formed of shanks 12 extending longitudinally in the unit, and oppositely projecting connecting arms 13 similar to the connecting arms 7 and connected with the shanks by similar inner bent portions 14. Each of these sections is formed of a single length of wire and the shanks are twisted together at 75 adjacent their junctures with the arms 13 to provide an intermediate connection similar to the connection afforded by the integral bend 5 of the previously described structure. The otherwise free ends of the shanks 80 of each unit are connected with the curved junctures of the shanks and arms of a longitudinally adjacent unit by eye-loops 16 at their extremities disposed in vertical planes 85 and corresponding to the closed hooks 9. The connecting arms 13 are terminally bent 90 to form eyes 17 and 18 corresponding respectively to the eyes 10 and 11 of the connecting arms 7. The shank sections at the sides of their mutually twisted portions 15 95 are slightly divergent to increase the transverse yielding action of the fabric upon application of load, and it is noted that in this form the transverse yielding action is also facilitated by the disposition of the connecting portions of the shanks in the general horizontal plane of said shanks and of the fabric, to avoid a twisting strain due to transverse pull on the shanks.

I claim:

1. A wire fabric comprising a plurality of interengaging units, each unit comprising a pair of shanks arranged adjacent each other, arms extending outwardly in opposite directions from the ends of the shanks, the other ends of the shanks being overturned to form hooks in parallel planes spaced from the plane of the shanks, and an integral connecting hook-shaped loop joining the ends of said first-mentioned hooks and serving to close the mouths of said hooks, said connecting loop extending in a plane spaced from the plane of said shanks so as to be positioned substantially in the plane of the outwardly extending arms of the adjacent unit, whereby upon separation of said last-mentioned ends of said shanks said loop will yield both torsionally and by straight deflection.

2. A wire fabric comprising a plurality

of interengaging units, each unit comprising a pair of shanks arranged adjacent each other, arms extending outwardly in opposite directions from the ends of the shanks, each 5 arm formed with a curved elbow whereby the arm may be longitudinally extended under stress, the other ends of the shanks being overturned to form hooks in parallel planes spaced from the plane of the shanks, 10 and an integral connecting hook-shaped loop joining the ends of said first-mentioned hooks and serving to close the mouths of said hooks, said connecting loop extend-

ing in a plane spaced from the plane of said shanks so as to be positioned substantially 15 in the plane of the outwardly extending arms of the adjacent unit, whereby upon separation of said last-mentioned ends of said shanks said loop will yield both torsionally and by straight deflection. 20

In testimony whereof I affix my signature in the presence of two witnesses.
